UNITED STATES PATENT OFFICE.

JOSEPH LIZOTTE, OF QUINCY, MASSACHUSETTS, ASSIGNOR OF ONE-HALF
TO MELLEN N. BRAY, OF BOSTON, MASSACHUSETTS.

VAPORIZER FOR EXPLOSIVE-ENGINES.

SPECIFICATION forming part of Letters Patent No. 703,937, dated July 1, 1902.

Application filed November 21, 1901. Serial No. 83,089. (No model.)

To all whom it may concern:

Be it known that I, JOSEPH LIZOTTE, of Quincy, in the county of Norfolk and State of Massachusetts, have invented certain new and useful Improvements in Vaporizers, of which the following is a specification.

The invention relates to vaporizing devices such as are used in connection with gasolene or hydrocarbon engines to effect the mixing of the air and gasolene-vapor introduced into the cylinder of the engine. Devices of this character are provided with a mixing-chamber into which the air and gasolene are introduced and from which the intermingled air and vapor pass into the cylinder on the feeding stroke of the piston. Heretofore the inlets for the air and gasolene have been so arranged that gasolene was liable to collect in the mixing-chamber after the flow of intermingled air and vapor ceased, which gasolene would be carried into the cylinder on the next flow to the cylinder, causing the engine to smoke or otherwise interfering with the proper action of the engine. One of the objects of the invention is to overcome this objection and to provide a vaporizing device in which there shall be no danger of gasolene collecting in the mixing-chamber. This is accomplished by introducing the gasolene into the air-passage in advance of the air-valve, so that any excess of gasolene flowing through the gasolene-inlet after the flow of air and vapor to the cylinder has ceased will not enter the mixing-chamber until the next opening of the air-valve, when it will be vaporized and mingled with the air before passing to the cylinder.

A further feature of invention consists in arranging the gasolene-valve above the air-valve and providing a spreader, which directs the gasolene into the current of inflowing air, so that it is more effectively vaporized and mingled with the air.

Further features of the invention relate to the arrangement and construction of the parts, as will be more particularly set forth in the claims.

In the accompanying drawing one simple

and efficient form of vaporizing device is shown embodying all the features of invention.

In the drawing the figure shows a vertical section of the vaporizing device.

In the view, A indicates the casing which forms the walls of the mixing-chamber B and in which the inlets for the air and gasolene and the outlet for the mingled air and vapor are formed and in which the air and gasolene valves are mounted. The inlet C for the air is screw-threaded for connection with a pipe leading from the usual source of hot-air supply, and the air passage or chamber D communicates with the mixing-chamber through an air-valve E, located in the top of the mixing-chamber.

The valve E is provided with a valve-stem e, which passes down through the mixing-chamber and through a plug F, screwed into an opening in the bottom of the casing A. The valve is held yieldingly to its seat by a coiled spring e', surrounding a boss f on the plug F and having one end engaging the plug and the other engaging the lower side of the valve.

The inlet G for the gasolene is screw-threaded for connection with a pipe leading from a source of gasolene-supply, and the passage g from the gasolene-inlet communicates with the air passage or chamber D. The supply of gasolene delivered through the passage g may be regulated by an adjustable valve H, arranged in said passage and having a head h outside the casing. The passage g enters the chamber D directly above the valve E and is normally closed by a gasolene-valve I, which is conical in shape and fits a conical valve-seat at the mouth of the passage g. The conical surface of the valve is extended to form a spreader J, which directs the gasolene flowing through the passage g to the outer periphery of the valve E, and consequently into the current of air flowing between the valve and its seat.

The valve I is provided with a valve-stem i, which extends down through the valve-stem e of the air-valve, and the valve is held to its seat by a spring i', surrounding the

valve-stem *i* and having one end bearing on the bottom of a recess in the valve *E* and the other end engaging the under side of valve *I*.

The valve-stem *i* is provided with an adjustable shoulder in the form of a nut *i*², screwed onto the end of the valve-stem and arranged a slight distance below the end of the valve-stem *e*. The nut *i*² may be adjusted to vary the space between the end of valve-stem *e*, and the nut is held in adjusted position by a lock-nut *i*³. The spring *e'* is stronger than the spring *i*², so that both valves will be normally held to their seats. With this manner of connecting the valves the valve *I* will be opened by the valve *E* after it has partially opened, and the valve *I* will close tightly in advance of the valve *E*. The relative movement between the valves in opening and closing may be accurately adjusted by the adjustment of nut *i*².

The mingled air and vapor pass from the mixing-chamber through the outlet *K*, which leads from the bottom of the mixing-chamber and is screw-threaded for connection with a pipe leading to the cylinder of the engine.

When the feeding stroke of the piston takes place, the forward movement of the piston causes the valve *E* to open and the air to flow past the valve into the mixing-chamber, and thence to the engine-cylinder. After the valve *E* has opened slightly and the flow of air past the valve has begun the valve *I* is opened and the gasoline flows down over the spreader *J* into the current of inflowing air, with which it is mingled and by which it is carried onward into the mixing-chamber. As the forward movement of the piston ceases the valve *E* returns to its seat and by this movement first closes the valve *I*. Any gasoline which is flowing down the spreader *J* when the valve *E* closes or which may leak by the valve *I* before the next opening of the valve *E* will collect above the valve *E*. Any such gasoline will flow over the edge of the valve *E* as soon as this valve is next opened and will mingle with the air which flows past said valve and be carried to the mixing-chamber. With this arrangement, therefore, there will be no collecting of gasoline in the mixing-chamber to interfere with the proper working of the engine.

The location of the gasoline-valve in the air-passage is advantageous in that the valve is at all times in contact with the hot air, resulting in a freer flow of the gasoline and a more ready vaporization thereof.

The conical surface below the gasoline-valve not only acts to direct the gasoline into

the current of inflowing air, but being subjected to the hot air it presents a heated surface which facilitates the vaporization of the gasoline flowing over it.

What I claim, and desire to secure by Letters Patent, is—

1. In a vaporizing device the combination of a mixing-chamber, an air-chamber, above the mixing-chamber, an air-valve between said chambers provided with a stem extending outside the mixing-chamber, a gasoline-valve above the air-valve having a stem extending through the stem of the air-valve and provided with a shoulder for determining the movement of the air-valve with relation to the gasoline-valve, a spring between the valves, and a spring for holding the air-valve to its seat, substantially as described. 75

2. In a vaporizing device the combination of a mixing-chamber an air-chamber, an air-valve between said chambers, a gasoline-valve above said air-valve having a spreading-surface extending substantially to the periphery of the air-valve, and connections between said valves whereby the air-valve opens before and closes after said gasoline-valve, substantially as described. 80

3. In a vaporizing device the combination of an air-valve having a stem, a gasoline-valve on the opposite side of the air-valve from said stem, a spring tending to separate said valves, and a connection between said valves allowing a limited relative movement between said valves, substantially as described. 90

4. In a vaporizing device the combination of a mixing-chamber *B*, an air-chamber *D*, an air-valve *E* between the chambers provided with a stem *e* extending outside the chamber *B*, a gasoline-valve *I* above valve *E* having a stem *i* extending through stem *e* and provided with an adjustable shoulder *i*², a spring *i*² between the valves and a spring *e'* for holding valve *E* to its seat, substantially as described. 95 100

5. In a vaporizing device the combination of an air-valve provided with a hollow stem, a gasoline-valve having a stem extending through said hollow stem and having a shoulder for engaging the end of said hollow stem, and a spring between said valves, substantially as described. 105

In testimony whereof I have affixed my signature in presence of two witnesses.

JOSEPH LIZOTTE.
